UNITED STATES PATENT OFFICE.

GEORGE W. LEACH, OF STONINGTON, ILLINOIS, ASSIGNOR OF ONE-HALF TO OSCAR W. KIDD, OF STONINGTON, ILLINOIS.

GRAIN-SHOCKER.

1,282,883.

Specification of Letters Patent.

Patented Oct. 29, 1918.

Application filed September 27, 1916. Serial No. 122,479.

To all whom it may concern:

Be it known that I, GEORGE W. LEACH, a citizen of the United States, residing at Stonington, in the county of Christian and State of Illinois, have invented certain new and useful Improvements in Grain-Shockers, of which the following is a specification, reference being had to the accompanying drawings.

10 This invention relates to an improved grain shucker and has for its primary object to provide a simple and positively operating mechanism to be substituted for the grain carrier as employed on an ordinary 15 binder, whereby the grain bundles may be collected into shocks and discharged upon the ground.

It is a more particular object of the invention to provide a device for the above purpose embodying a rotatably mounted vertical shaft, a shock former pivotally supported upon the upper end of said shaft and bodily movable by said shaft to its discharging position, and means for tilting the former as it moves to its discharging position whereby the shock is discharged or dumped upon the ground.

It is a further general object of the invention to provide mechanism for the above purpose which is very simple in its construction and not liable to get out of order, and can be manufactured or applied to the ordinary grain binder at relatively small cost.

With the above and other objects in view, 35 my invention consists in the novel features of construction, combination and arrangement of parts to be hereinafter more fully described, claimed and illustrated in the accompanying drawing, in which,

40 Figure 1 is a side elevation illustrating the preferred embodiment of my improved grain shucker;

Fig. 2 is a top plan view, the shock former being shown in dotted lines in its discharging position;

Fig. 3 is a transverse section taken on the line 3—3 of Fig. 2, the shock former being in its discharging position;

Fig. 4 is a detail horizontal section taken 50 on the line 4—4 of Fig. 3; and

Fig. 5 is an inverted perspective view of the shock former.

Referring in detail to the drawing, 5 designates a suitable frame mounted upon an 55 axle 6, said axle being supported by means

of the ground wheels 7 fixed upon the opposite ends thereof.

Upon one side of the frame 5, a perpendicular shaft 8 is rotatably mounted in spaced bearings 9. The shock former 10 is 60 preferably constructed of sheet metal and is of semi-circular form in cross section, one end of the former being closed by the wall 11 and the other end of the former being open. At a point intermediate of its ends, 65 a metal strap 12 is secured to the exterior face of the shock former and is closely engaged with one side thereof. The strap 12 extends beneath the former and in spaced relation to its opposite side wall as indicated 70 at 13 and is then vertically extended as at 14 and riveted or otherwise fixed to the side edge of the former. The upper end of said strap is pivotally engaged upon a stud bolt 15 fixed in the upper end of the perpendicular shaft 8.

To the lower end of said shaft 8 a beveled gear 17 is secured. A similar beveled gear 18 is loosely engaged upon the wheel axle 6 and has a sleeve or hub portion journaled 80 in a suitable bearing on the frame 5. The end face of this hub is formed with clutch teeth indicated at 19. A clutch sleeve 20 is keyed upon the wheel axle 6 and the clutch teeth 21 on one end thereof are adapted for 85 engagement with the opposed clutch teeth 19 on the gear 18. The sleeve 20 is provided with a flange or collar 22 with which the bifurcated end of a clutch shifting lever 23 is engaged. A suitable operating rod 24 is 90 connected to this lever and is adapted to be actuated by the driver to shift the sliding clutch member into locking engagement with the gear 18.

To one side of the frame 5, the extremity 95 of a curved rod 25 is suitably secured, the medial portion of the rod extending above the frame.

In the operation of the device, the grain bundles are deposited in any suitable manner into the shock former 10. When a sufficient number of bundles have been collected therein, the operator shifts the clutch sleeve 20 into interlocking engagement with the gear 18 so that said gear meshing with the 100 gear 17 will transmit rotation to the perpendicular shaft 8. The shock former 10 will thus be swung laterally and the horizontal portion 13 of the strap 12 will engage the trip rod 25 so that in the further turn- 110

ing movement of the shock former, the same will be tilted to an inclined position, as shown in Fig. 3 to dump the shock upon the ground. The turning movement of the shock former is continued until the same is again disposed in its original bundle receiving position. A brake spring indicated at 25 is provided to engage the vertical shaft 8 and prevent its continued rotation when 10 the clutch 20 is shifted to its inoperative position.

From the foregoing description, taken in connection with the accompanying drawing, the construction, manner of operation, and 15 several advantages of the invention will be clearly and fully understood. The device, while quite simple in its construction, is nevertheless handy, reliable and efficient in practical operation and provides means for 20 easily and quickly depositing the grain bundles in shocks upon the field in the travel of the binder. The device may be readily substituted in lieu of the ordinary grain carrier without necessitating any material alterations in the binder construction. It will 25 also be manifest that the mechanism is quite durable in practical use and capable of manufacture at relatively small cost. While I have above described the preferred construction and arrangement of the several elements it is to be understood that the de-

vice is susceptible of considerable modification therein and I, therefore, reserve the privilege of adopting all such legitimate changes as may be fairly embodied within 35 the spirit and scope of the invention as claimed.

I claim:

In a grain shocker, in combination with a wheel supported platform, a perpendicular 40 shaft rotatably mounted upon one side of said platform and extending above the same, a bundle receiver movable over the platform, an angular bar extending under the bundle receiver and fixed at one of its ends thereto, 45 means for pivotally mounting the other end of the bar upon the upper end of said shaft to support the bundle receiver for angular tilting movement, means for rotating said shaft, and a trip rod fixed to the side of the 50 platform in spaced relation to the shaft and adapted to be engaged by said bar at a pre-determined point in the movement of the receiver over the platform to tilt the receiver and discharge the bundles therefrom at one 55 side of the platform.

In testimony whereof I hereunto affix my signature in the presence of two witnesses.

GEORGE W. LEACH.
